UNITED STATES PATENT OFFICE.

CARL PREUSS, OF BERLIN, PRUSSIA, GERMANY, ASSIGNOR TO REINHOLD ZIRNGIEBEL, OF SAME PLACE.

MACHINE FOR TURNING FLAT-SIDED OBJECTS.

SPECIFICATION forming part of Letters Patent No. 236,079, dated December 28, 1880.
Application filed October 22, 1880. (No model.)

To all whom it may concern:

Be it known that I, CARL PREUSS, of the city of Berlin, in the Kingdom of Prussia and Empire of Germany, have invented a certain new and useful Improvement in Machines for Turning Flat-Sided Objects, of which the following is a specification.

The purpose of my invention is to produce a machine for turning flat - sided objects, which can be readily adjusted for holding objects of different length, and in which the objects can be secured to and removed from the machine separately and will be firmly held in position, so as to be incapable of disarrangement while the cutting is being performed.

My invention consists in the peculiar novel devices employed by me for this purpose, as fully hereinafter explained, and pointed out by the claims.

20 In the accompanying drawings, forming a part hereof, Figure 1 is a side elevation of the machine with one baluster in position; Fig. 2, an end view of the machine, one of the holding-disks being removed and twelve 25 balusters being shown as secured to the remaining disk; Fig. 3, a vertical central section of one holding-disk, and Fig. 4 a face-view of the clamping-plate.

Like letters denote corresponding parts in 30 all the figures.

The parts of the machine are mounted on a shaft, *a*, which may be held between centers or journaled in suitable boxes.

Large disks, *b b*, are fixed adjustably upon 35 the shaft *a* by means of keys *e* sliding in seats *e'* cut in the shaft, and held in the disks by upturned ends and set-screws *d*, which turn through the hubs of the disks and force the keys against their seats. Each disk has a 40 flange, *c*, on its inner side, whose periphery is polygonal in shape. These flanges have a number of flat surfaces equal to the number of balusters or other flat-sided objects that can be turned at one time, the flat surfaces of 45 the two disks being arranged opposite each other.

To the peripheries of the disks are secured toothed clamping-plates *g*, (one for each flat surface of the flanges *c*), which are held by 50 nuts and bolts *h*, and project beyond the inner sides of the disk.

The disks are arranged the proper distance apart to receive between them the objects to be turned, and are then rigidly secured to the shaft. The blanks *f* are then placed on the 55 flat surfaces of the flanges *c*, and are clamped in position by the plates *g*. All the surfaces of the flanges *c* are thus filled, and the blanks form a cylinder, being parallel with the shaft *a*, and having their outer surfaces arranged at 60 right angles to radial lines.

A pattern for cutting by may be secured to one of the blanks.

The shaft *a* being revolved, one side of the blanks is cut to the desired shape. All the 65 blanks except one are then turned so as to present another side outward, the blank not turned serving as a guide to form the others by. This operation is repeated until all sides of the objects are shaped, when they are removed from the machine and a new set of blanks put in their place.

The disks, it will be seen, can be adjusted to accommodate objects of any length.

Objects having four sides, or any greater 75 even number of sides, can be turned on the machine.

If it is desired to turn objects having three, five, or any other odd number of sides, the seats on the flanges *c* can be made to receive 80 any angle instead of the flat side of each object.

By having seats on the disks of the shape of the ends of the objects they can be rigidly held, so that there can be no displacement in 85 cutting. The objects being held by separate clamping-plates, they can be secured to and removed from the machine separately, and can be more conveniently handled and more accurately arranged than when a single clamping-ring is used to secure each end of all the objects. The means for holding the disks to the shaft permit of a ready adjustment of such disks, and at the same time prevent the shifting of the disks axially on the shaft, the seats 90 of each pair being always kept exactly opposite each other.

What I claim as my invention is—

1. In a machine for turning flat-sided objects, the combination, with the shaft *a*, of the 100 disks *b*, adjustable thereon, and having flanges *c*, provided with flat seats for receiving the

0
ends of the objects, and the clamping-plates *g*, one for each of said seats, substantially as described and shown.

2. In a machine for turning flat-sided objects, the combination, with the shaft *a*, having key-seat *c'*, of the disks *b*, having flanges *c*, provided with flat seats, and having, further, the separate clamping-plates *g*, one for each seat, the keys *e*, and set-screws *d*, all con-

structed and arranged substantially as described and shown.

In testimony whereof I have signed my name to this specification in the presence of two subscribing witnesses.

CARL PREUSS.
